LINE-FORMING MECHANISM FOR
TYPEWRITING MACHINES

George E. Canham, West Orange, N. J., assignor
to Ralph C. Coxhead Corp., Newark, N. J., a
corporation of Delaware

Application May 15, 1951, Serial No. 226,368

16 Claims. (Cl. 197—113)

1

This invention relates to typewriting machines particularly adapted for type composition and, more particularly, to a machine for composing forms or lists which are to be reproduced. While the invention as illustrated is embodied in a composing machine known in the trade as the "Varietyper," the invention in its broader aspects is applicable to other typewriting machines as well.

In composing forms on the "Varietyper," various sizes and styles of type are available and may be readily interchanged so as to produce legible and attractive-appearing forms and lists. The present invention is directed to the provision of means for rapidly and easily typing leaders (a row of dots or dashes to carry the eye between two columns of print) or rules (full lines) with a typewriter, which lines compare favorably in appearance with those produced by set type or by ruling a photographic negative made from typed copy.

Among the objects of the invention are to provide a typewriting machine that will form leaders, rules, and double rules; that will form such lines automatically without the necessity of hitting a key for each impression; that will stop automatically when the line is completed; and to provide such a construction on a rear-strike typewriter such as the "Varietyper."

Other objects of the invention are to provide a generally improved mechanism for rapidly and easily inserting leaders and rules during the composition of a form or list, and to provide such a mechanism that is simple and dependable in operation and that will produce lines of good uniformity and proper contrast.

Further objects and objects relating to details and economies of construction, manufacture, and use will more definitely appear from the detailed description to follow.

The "Varietyper" is a typewriting machine of the rear-strike variety, in which raised type symbols are formed on the cylindrical surface of a type shuttle which is mounted in front of a paper carriage adapted to be moved past the printing point. The shuttle, which is mounted for rotation about its axis, is rotated to index any selected symbol at the printing point, and a type ribbon is passed between the shuttle and the carriage. The carriage is of the open type, in which both the front and the back of the paper are exposed at the printing point and a hammer located behind the carriage moves forwardly to strike the paper against the ribbon and shuttle to form the printed impression.

In the form shown of the present invention, 55 leaders and rules.

2

leader dots or ruled-line segments are formed on the type shuttle, preferably being indexed at the printing point when the shuttle is in its normal position (not indexed for printing of symbols controlled by the keys). Mechanism is provided for successively operating the hammer and the carriage-spacing mechanism so as to rapidly form a series of type impressions of the sort desired across the paper. In conjunction with this mechanism, an automatic stop is provided to disable the impression-forming mechanism at any desired point. Preferably, the control mechanism is electrical, the hammer mechanism and spacing mechanism being operated or released by a solenoid and an electrical circuit to the solenoid being successively interrupted to cause successive operation of the solenoid, each operation of the solenoid causing the symbol to be printed a single time. An electric switch actuated by a cam settable along the length of the carriage serves to open the circuit when the carriage has reached a predetermined point, so as to stop printing of the line at any desired point.

25 My invention is clearly defined in the appended claims. In the claims, as well as in the description, parts are at times identified by specific names for clarity and convenience, but such nomenclature is to be understood as having the broadest meaning consistent with the context and with the concept of my invention as distinguished from the pertinent prior art. The best form in which I have contemplated applying my invention is illustrated in the accompanying drawings forming part of this specification, in which:

Fig. 1 is a top plan view of a typewriter according to the present invention, portions of the typewriter being broken away or omitted for clarity and convenience of illustration.

Fig. 2 is a sample form illustrating the kinds and quality of leaders and rules that can be formed by the machine of the present invention.

Fig. 3 is a side elevation of a portion of the type shuttle.

Fig. 4 is a top plan view of the type shuttle portion shown in Fig. 3.

Fig. 5 is a wiring diagram of the hammer release control mechanism of the present invention.

Fig. 6 is a somewhat diagrammatic perspective view of the mechanical linkage for operating the hammer and controlling the spacing mechanism in connection with the printing of leaders and rules.

Fig. 7 is a somewhat diagrammatic fragmentary elevation of the mechanism for suppressing the hammer action when printing leaders and rules.

Fig. 8 is a somewhat diagrammatic elevation of the switch and associated parts for automatically terminating a line at any desired point.

Referring now to Fig. 1, the general organization of the typewriter with which the present invention is associated will be briefly described. This typewriter, which is known to the trade as a "Varietyper," has a frame 11 for supporting the various component parts of the machine. A housing 12 covers the frame and most of the interior moving parts of the machine to protect these parts against damage, as well as to contribute to a pleasing over-all appearance. This housing is preferably formed in several parts for accessibility of the interior mechanism.

Key levers 14, only a few of which are shown, are preferably mounted on a knife edge 15 (Fig. 6), actuation of each key lever effecting the printing of the type character associated therewith. The key board of this typewriter is also provided with a space bar 16 and capital and figure shift keys 17 and 19, respectively, for altering the case of type at the printing point 20.

In this machine, the type characters are embossed in three rows upon a type shuttle 21 mounted for oscillation along the cylindrical surface of an anvil 22, so as to selectively present characters at the printing point. One row or case of embossed type characters is normally opposite the printing point, and the other two rows of characters are moved to position opposite the printing point by operation of the capital and figure shift keys to raise the anvil and shuttle.

A hammer 25 coacts with the type shuttle 21 to drive paper interposed therebetween against the shuttle at the printing point 20 in order to form a type impression. A pigment ribbon 26 is interposed between the paper and the shuttle 21 to supply ink for the printing operation.

The paper is carried past the printing point 20 and supported in position between the shuttle 21 and the hammer 25 by a movable paper carriage 27, this carriage progressing a short distance after each printing impression or for spacing between words in order to properly space the printed characters.

The carriage 27 is mounted on guide rails (not shown) and is biased towards the left, its movement towards the left being restrained by an escapement mechanism which is actuated upon forming a printed impression so as to release the carriage for movement a short distance in order to properly space the characters.

The hammer 25 is biased towards the shuttle 21 so that, upon depression of a printing key, the shuttle is first indexed to present the corresponding symbol at the printing point, and the hammer is released to swing forward on a horizontal pivot (not shown) and strike the paper against the shuttle to form the printed impression. After forming the impression, the hammer is returned to rearward position by a drive mechanism, including a spring motor 29 intermittently wound by an electric motor 30. Movement of the hammer is controlled by a hammer escapement mechanism (not shown) which is tripped by operation of any of the key levers 14. The hammer escapement mechanism is disclosed in U. S. patent to Trego 1,965,677.

The escapement mechanism of the typewriter

shown in Fig. 1 is shown and more completely described in U. S. patent to Norton 2,581,200 and provides for a differential spacing of the various characters of a type font in accordance with their individual spacing requirements. This mechanism comprises a single escapement wheel and a movable dog and fixed dog alternately engaged with the escapement wheel. Retrograde movement of the movable dog when disengaged from the escapement wheel is varied by a series of stops which may be interposed in the path of the dog so as to limit its retrograde movement, and thus control the escapement and carriage movement permitted upon forward movement of the dog. Forward movement of the hammer for the printing stroke, operating through a mechanical linkage, disengages the movable dog from the escapement wheel and engages the fixed dog, and return movement of the hammer re-engages the movable dog and disengages the fixed dog so as to permit spacing movement of the carriage. A detailed illustration and description of the operation of the escapement mechanism and its control by the hammer movement is contained in the above-mentioned U. S. Patent 2,581,200.

According to the present invention, the typewriter described in the immediately preceding seven paragraphs is provided with mechanism for quickly and easily forming leaders and single and double rules. Fig. 2 illustrates a typical specimen form having leaders 31, single rules 32, and double rules 34; certain of the rules being horizontal and others being vertical. The form of Fig. 2 may be completely composed with a machine according to the present invention, the type shuttle 21 being changed as required to obtain the various sizes and styles of type required. The horizontal lines are preferably typed while composing the written matter, and the vertical lines are preferably formed later by removing the paper from the carriage and reinserting it in sideways position, so that the top and bottom of the sheet are at the sides of the carriage.

Referring to Figs. 3 and 4, the shuttle 21 is formed of an arcuate strip 35 having the various type symbols embossed thereon, the strip 35 being mounted on a flat web 36. In indexing the shuttle 21 when typing, the inner surface of the strip 35 is moved along the surface of the anvil 22 (Fig. 1) to index the selected type symbol at the printing point 24.

Referring to Fig. 3, three rows or cases of type symbols are provided on the surface of the shuttle, the uppermost row or case 37 printing the lower case or small letters, the middle row or case 39 printing the upper case or capital letters, and the lowermost row 40 printing the figures and symbols. The type shuttle is indexed either to the right or to the left for the printing of any symbol appearing on the type keys, leaving a vertical central zone or portion 41 which is in front of the printing point when the shuttle is in its normal or unindexed position.

According to the present invention, embossed symbols are formed in the zone 41 of the type shuttle, these symbols preferably comprising two closely spaced leader dots 42 in the lower case row of symbols 37 for the forming of leaders 31 shown in Fig. 2, a short horizontal line 44 in the upper case row of symbols 39 for forming single rules 32, and a pair of short, parallel, horizontal lines 45 in the figure row of symbols 40

for forming double rules 34. The symbols 42, 44, and 45 may each be printed without indexing the shuttle 21 about the anvil 22, the desired symbol of the three being selected by operation or nonoperation of the "cap" shift key 17 and the "figure" shift key 19.

As above mentioned, a type impression is formed by forward movement of the hammer 25 so as to drive the paper against the pigment ribbon 26 and shuttle 21. The hammer 25 is normally in its rearward position and is urged forwardly towards the paper by a hammer spring (not shown) and is returned to rearward position against the bias of the hammer spring by the spring motor 29. The hammer is restrained by hammer escapement mechanism which is clearly disclosed in U. S. Patent to Trego 1,965,677, operation of the hammer escapement mechanism being controlled by the hammer escapement operating lever 46. Actuation of the lever 46 causes the hammer 25 to move forwardly for a single printing and return stroke.

Depression of any of the key levers 14 first indexes the shuttle and then actuates the lever 46 to release the hammer 25 and form an impression of the selected symbol. In addition, the lever 46 is actuated by mechanism, to be described, for forming impressions of the symbols within the central zone 41 of the shuttle when the shuttle is not indexed. Forward movement of the hammer 25 in its printing stroke initiates carriage escapement for spacing movement, and return movement of the hammer completes the escapement cycle so as to cause spacing movement of the carriage only after the printed impression has been formed. The mechanism interconnecting the hammer and the carriage escapement mechanism is illustrated and described in U. S. Patent 2,581,200.

According to the preferred form of the present invention, in the printing of symbols 31, 32, and 40 the hammer escapement operating lever 46 is actuated by electrical means, preferably by a solenoid 47 operating through a link 49 and a bell crank lever 50 pivoted on the frame 11, movement of the hammer in turn actuating the carriage-spacing escapement mechanism. Energizing the solenoid 47 serves to draw the link 49 to the right as viewed in Fig. 6, the bell crank lever 50 being rotated counterclockwise about its pivot 52 so as to depress the hammer escapement operating lever 46 and actuate the hammer escapement mechanism to cause a printing stroke of the hammer. The spring 51, anchored to the frame 11 of the typewriter, biases the bell crank lever 50 clockwise about its pivot 52 so as to return the lever 50 and link 49 when the solenoid 47 is no longer energized.

It is preferable when printing any of the symbols 42, 44, and 45 to suppress the hammer action somewhat, so as to obtain a lighter printed impression. Accordingly, a hammer suppressor 54 (Figs. 6 and 7) may be linked to the bell crank lever 50, the suppressor having a bifurcated end 55 extending on each side of a hammer check rod 56 pivoted to the hammer and extending downwardly through an opening in the frame 11. The hammer check rod 56 is drawn upwardly as the hammer moves forward to form a printed impression, and an enlargement 58 on the end of the rod is drawn upwardly against the bifurcated end 55 of the hammer suppressor 54 to limit and arrest forward movement of the hammer. The bifurcated end 55 of the hammer suppressor may have a thinner zone 57 engaged by the enlarge-

ment 58 on the check rod 56 when printing letters and other symbols and a somewhat thicker zone 59 moved into operating position by rotation of the bell crank lever 50 to arrest forward movement of the hammer somewhat sooner when printing the symbols 42, 44, and 45, so as to form a somewhat lighter impression of these latter symbols.

The spacing requirements of the symbols 42, 44, and 45 are three arbitrary escapement or spacing units, equal to, and produced by, the rotation of the escapement wheel for a distance of three teeth. Accordingly, the escapement mechanism described in U. S. Patent 2,581,200, which is in part shown in Fig. 6, is modified to provide a projecting arm 60 on the three-unit-space movable stop 61. A projection 62 on the link 49 engages the arm 60 of the stop 61 as the link moves to the right (Fig. 6), so as to rotate the stop into the path of the movable dog of the escapement mechanism upon actuation of the solenoid 47, which limits the carriage-spacing movement to three spacing units upon actuation of the solenoid 47.

Operation of the solenoid 47 is controlled by an electrical circuit, including two contact buttons 64 and 65, these buttons being mounted on a box-like housing 66 at the right side of the keyboard (Fig. 1). Depression of the button 64 actuates the solenoid a single time for a single printing of any of the symbols 42, 44, and 45, while actuation of the button 65 causes repeated actuation of the solenoid 47 to form a leader 31, single rule 32, or double rule 34 of any desired length. If desired, the button 65 may be depressed until the desired line is of nearly the proper length, causing rapid repeated actuation of the hammer; and then the button 64 may be depressed one or more times to produce a line of the exact length desired.

The wiring circuit for actuating the solenoid 47 is shown in Fig. 5. This circuit includes a synchronous motor 67 within the housing 66 in series with a single pole, single throw switch 68, biased open and closed by depressing the button 65. A rotary cam 70, driven by the motor 67, repeatedly closes a single pole, single throw switch 71, which is normally biased open and is in series with the switch 68 so as to successively make and break an electrical circuit through the solenoid and cause repeated operation of the solenoid. The cycle of makes and breaks of this circuit is only a little longer than the time required for completion of the hammer cycle in forming a printed impression and return and may be operated at about six (6) makes and breaks per second. Accordingly, a printed impression is made each time this circuit is completed by the closing of switch 71.

A single pole, single throw switch 72, which is normally biased closed, may be mounted on the typewriter frame 11 (Figs. 1 and 8), this switch having a pivoted actuating arm 74 in the path of a cam 75 settable along the usual scale 76 mounted on the front of the carriage. The cam 75 may be set along the scale 76 so as to strike the actuating arm 74 when the carriage has reached a predetermined position at which it is desired to stop a line. Engagement of this cam with the arm 74 opens the switch 72 so as to break the circuit to the motor 67 and solenoid 47, thus disabling the repeat mechanism and preventing further actuation of the hammer, even though the button 65 is maintained depressed. Accordingly, if a series of leaders or rules are to be formed with their right ends in

alignment, the cam 75 may be set accordingly and the button 65 depressed so as to cause the machine to form a line of the desired length and then stop when the carriage 27 reaches a predetermined point.

The button 64 controls a single pole, double throw switch 77, one contact of which is in series with the circuit through the switch 71, the switch being biased to complete that circuit. Upon depression of the button 64, the circuit through the switch 71 is broken and a direct circuit is established through the solenoid 47 to energize the solenoid and cause a single printing of the symbols 42, 44, and 45, the circuit being broken upon release of the button 64. This button may be used when only one or several lines are to be formed and use of the cam 75 is not desired.

The power for the circuit in Fig. 5, used for energizing the solenoid 47, may be taken from the same power source as that used for the intermittently electrically operated motor 30, the motor 30 and the circuit of Fig. 5 being connected in parallel.

I claim:

1. A typewriting machine having a paper carriage movable step by step past a printing point, means for forming a printed impression at the printing point, carriage-spacing mechanism for progressing the carriage past the printing point after the forming of each impression, electrically operated mechanism for actuating the impression-forming means and the carriage-spacing mechanism, control means, including a constant-speed electric motor and a switch operated by said motor and in circuit with said electrically operated mechanism for repeatedly completing and opening an electric circuit through said electrically operated mechanism to cause repeated printing of a selected type symbol, and an electric switch operated responsive to carriage position for opening the circuit to the electrically operated mechanism when the carriage has reached a predetermined position.

2. A typewriting machine having a paper carriage movable step by step past a printing point, means for forming a printed impression at the printing point, carriage-spacing mechanism for progressing the carriage past the printing point after the forming of each impression, electrically operated mechanism for actuating the impression-forming means and the carriage-spacing mechanism, control means, including a constant-speed electric motor and a switch operated by said motor and in circuit with said electrically operated mechanism for repeatedly completing and opening an electric circuit through said electrically operated mechanism to cause repeated printing of a selected type symbol, and an electric switch operated responsive to carriage position for opening the circuit to the electrically operated mechanism when the carriage has reached a predetermined position, the interval between successive completions of the circuit to the electrically operated mechanism being a little longer than the time required for forming the printed impression and spacing movement of the carriage.

3. A typewriting machine having a paper carriage movable step by step past a printing point, means for forming a printed impression at the printing point, carriage-spacing mechanism for progressing the carriage past the printing point after the forming of each impression, typewriter keys for operating the impression-forming means and the carriage-spacing mechanism, a solenoid

alternatively operable for actuating the impression-forming means, and the carriage-spacing mechanism, and control means, including a constant-speed electric motor and a switch operated

5 by said motor for repeatedly completing and opening an electric circuit through said solenoid to cause repeated printing of a selected type symbol, the interval between successive completions of the solenoid circuit being a little longer than 10 the time required for forming the printed impression and spacing movement of the carriage.

4. A typewriting machine having a paper carriage movable step by step past a printing point, means for forming a printed impression at the 15 printing point, carriage-spacing mechanism for progressing the carriage past the printing point after the forming of each impression, typewriter keys for operating the impression-forming means and the carriage-spacing mechanism, a solenoid

20 alternatively operable for actuating the impression-forming means and the carriage-spacing mechanism, a switch in circuit with the solenoid for repeatedly completing and opening an electric circuit through said solenoid to cause repeated printing of a selected type symbol, a constant-speed electric motor solely driving said switch, and a switch controlling said motor.

5. A typewriting machine having a paper carriage movable step by step past a printing point, 30 means for forming a printed impression at the printing point, carriage-spacing mechanism for progressing the carriage past the printing point after the forming of each impression, a solenoid for actuating the impression-forming means and the carriage-spacing mechanism, a switch in circuit with the solenoid for repeatedly completing and opening an electric circuit through said solenoid to cause repeated printing of a selected type symbol, a constant-speed electric motor solely driving said switch, and a switch controlling said motor.

35 6. A typewriting machine having typewriter keys, a paper carriage movable step by step past a printing point, a movable type shuttle mounted at the printing point, said type shuttle being arcuate in form and having type symbols embossed thereon, means for indexing said type shuttle in either direction in response to actuation of the typewriter keys to present a selected symbol at the printing point, a hammer located behind the carriage and operable to drive the paper against the shuttle to form a printed impression, carriage-spacing means for progressing the carriage after forming a type impression, and 40 means for causing operation of the hammer and spacing movement of the carriage, said type shuttle being provided with a line-forming symbol normally indexed at the printing point and moved from the printing point upon indexing of the shuttle responsive to operation of a typewriter key.

45 7. A typewriting machine having typewriter keys, a paper carriage movable step by step past a printing point, a movable type shuttle mounted at the printing point, said type shuttle being arcuate in form and having type symbols embossed thereon, means for indexing said type shuttle in either direction in response to actuation of the typewriter keys to present a selected symbol at the printing point, a hammer located behind the carriage and operable to drive the paper against the shuttle to form a printed impression, carriage-spacing means for progressing the carriage after forming a type impression, and means for causing repeated operation of the hammer.

50 75 8. A typewriting machine having typewriter keys, a paper carriage movable step by step past a printing point, a movable type shuttle mounted at the printing point, said type shuttle being arcuate in form and having type symbols embossed thereon, means for indexing said type shuttle in either direction in response to actuation of the typewriter keys to present a selected symbol at the printing point, a hammer located behind the carriage and operable to drive the paper against the shuttle to form a printed impression, carriage-spacing means for progressing the carriage after forming a type impression, and means for causing repeated operation of the hammer.

and spacing movement of the carriage, said type shuttle being provided with a line-forming symbol normally indexed at the printing point and moved from the printing point upon indexing of the shuttle responsive to operation of a type-writer key.

8. A typewriting machine having typewriter keys, a paper carriage movable step by step past a printing point, a movable type shuttle mounted at the printing point, said type shuttle being arcuate in form and having type symbols embossed thereon, means for indexing said type shuttle in either direction in response to actuation of the typewriter keys to present a selected symbol at the printing point, a hammer located behind the carriage and operable to drive the paper against the shuttle to form a printed impression, carriage-spacing means for progressing the carriage after forming a type impression, means for causing repeated operation of the hammer and spacing movement of the carriage, and means operative upon the carriage reaching a predetermined point for disabling said last-mentioned means, said type shuttle being provided with a line-forming symbol normally indexed at the printing point and moved from the printing point upon indexing of the shuttle responsive to operation of a typewriter key.

9. In a rear-strike typewriter having a paper carriage, means for presenting a selected type symbol at a printing point, a hammer behind the carriage and operable to drive the paper against the type to form a printed impression, electrically operated mechanism for causing operation of the hammer and spacing movement of the carriage, control means in circuit with said electrically operated mechanism for repeatedly completing and opening an electric circuit through said electrically operated mechanism to cause repeated printing of a selected type symbol, and an electric switch operated responsive to carriage position for opening the circuit to the electrically operated mechanism when the carriage has reached a predetermined position.

10. In a rear-strike typewriter having a paper carriage, means for presenting a selected type symbol at a printing point, a hammer behind the carriage and operable to drive the paper against the type to form a printed impression, electrically operated mechanism for causing operation of the hammer and spacing movement of the carriage, means operated by said electrically operated mechanism for prematurely arresting the normal stroke of the hammer, and control means in circuit with said electrically operated mechanism for repeatedly completing and opening an electric circuit through said electrically operated mechanism to cause repeated printing of a selected type symbol.

11. A type shuttle for a rear-strike typewriting machine in which the shuttle is indexed to one side or the other in response to actuation of the typewriter keys, said type shuttle comprising: an arcuate strip having a font of type embossed thereon in two spaced groups symmetrically located one on each side of the central portion of the strip, and line-forming symbols embossed on the central portion of the strip between said two groups.

12. In a rear-strike typewriter having a paper carriage, means for presenting a selected type symbol at a printing point, a hammer behind the carriage and operable to drive the paper against

the type to form a printed impression, an electrically operated mechanism for causing operation of the hammer and spacing movement of the carriage, control means in circuit with said electrically operated mechanism for repeatedly opening and closing an electrical circuit through said electrically operated mechanism to cause repeated printing of a selected type symbol, a cam settable along the length of the carriage, and an electric switch in the path of the cam for opening the circuit to the electrically operated mechanism when the carriage has reached a predetermined position.

13. A type shuttle for a rear-strike typewriting machine in which the shuttle is indexed to one side or the other in response to actuation of the typewriter keys, said type shuttle comprising: an arcuate strip having a font of type embossed thereon in two spaced groups located one on each side of the central portion of the strip, the type within each group being arranged in at least two rows and the corresponding rows of said two groups being aligned, and line-forming symbols embossed on the central portion of the strip between said two groups, each of said symbols being aligned with one of the rows of type of each group.

14. A type shuttle for a rear-strike typewriting machine in which the shuttle is indexed to one side or the other in response to actuation of the typewriter keys, said type shuttle comprising: an arcuate strip having a font of type embossed thereon in two spaced groups symmetrically located one on each side of the central portion of the strip, and at least one line-forming symbol embossed on the central portion of the strip between said two groups.

15. A typewriting machine having a paper carriage movable step by step past a printing point, means for forming a printed impression at the printing point, carriage-spacing mechanism for progressing the carriage past the printing point after the forming of each impression, a solenoid for actuating the impression-forming means and the carriage-spacing mechanism, a first electric circuit to the solenoid, a constant-speed electric motor, a switch operated by the motor and in the first solenoid circuit for repeatedly completing and interrupting said circuit, an electric circuit to the motor, a manually operated switch in the motor circuit for controlling operation of the motor, a second electric circuit to the solenoid, and a multiposition switch common to both circuits to the solenoid, biased to complete the first circuit and operable to interrupt the first circuit and complete the second circuit.

16. A typewriting machine as claimed in claim 15, having a switch in the first solenoid circuit, said switch being biased to closed position and opened in response to movement of the paper carriage upon the carriage reaching a predetermined position.

GEORGE E. CANHAM.
